UNITED STATES PATENT OFFICE.

ANTON J. ROKUSEK, OF TABOR, SOUTH DAKOTA.

CORN-HUSKER.

SPECIFICATION forming part of Letters Patent No. 787,793, dated April 18, 1905.

Application filed December 31, 1904. Serial No. 239,172.

To all whom it may concern:

Be it known that I, ANTON J. ROKUSEK, a citizen of the United States, residing at Tabor, in the county of Bonhomme, State of South Dakota, have invented certain new and useful Improvements in Corn-Huskers; and I do hereby declare the following to be a full, clear, and exact description of the invention, such as will enable others skilled in the art to which it appertains to make and use the same.

This invention relates to corn-huskers, and more particularly to hand corn-huskers, and has for its object to provide a device of this nature which may be manufactured at a low figure and which will be simple in arrangement.

Another object is to provide a husker with which the husks may be positively grasped when being removed.

Other objects and advantages will be apparent from the following description, and it will be understood that changes may be made in the construction shown and that any suitable material may be used without departing from the spirit of the invention.

In the drawings forming a portion of this specification, and in which like numerals of reference indicate similar parts in the several views, Figure 1 is a plan view of the invention with the straps unfastened. Fig. 2 is a perspective view of the invention in use and showing the hooks. Fig. 3 is a view similar to Fig. 2, showing the back of the hand. Fig. 4 is a sectional view of the adjustable hook.

Referring now to the drawings, the present invention comprises a piece of rawhide or other suitable material, having the general form of a quadrilateral, the sides thereof being somewhat longer than its base. The triangular portion is indicated at 5, and in its base this portion has, adjacent to its side 8, an arcuate cut-away portion 7, which when the device is in use forms a thumb-hole. Between the cut-away portion 7 and the side 8 of the portion 5 the latter is split, as shown at 9, to form straps 10 and 11, and secured to the portion 6, which lies between the cut-away portion and the side 12 of the portion 5—this side lying opposite to the side 8—are straps

13 and 14, which extend beyond the edge of 50 the portion 5.

As shown, the apex of the triangle is cut away on a line extending at a slightly obtuse angle to the side 8, and adjacent to the side 8 the portion 5 is cut into from its minor end, 55 as shown at 15, to form a partly-separated portion 16, and secured to the outer end of this portion there is a strap 17. Secured to the portion 5 adjacent to its side 12 and projecting beyond the minor end thereof there is a strap 18, 60 and secured to the portion 5, adjacent to its minor end and between the strap 18 and the cut 15, are buckles 19 and 20. The straps 10 and 11 are also provided with buckles 21 and 22, respectively.

Secured to the outer face 5' of the portion 5, centrally thereof, there is a metallic plate 23, having the usual form of adjustable hook 24 attached thereto, with its point directed toward the side 8 of the portion 5. The hook 24 is located adjacent to the corner of the plate which lies nearest to the side 8 of the portion 5 and to the cut-away portion 7. Secured to the outer face of the portion 5, adjacent to the cut-away portion 7 and projecting beyond the side 8, there is a plate 25, 70 having its outer end sharpened and turned outwardly and backwardly over itself to form a hook. A reinforcing-strip 26 is secured to the portion 5 between the plate 25 and that portion. Secured to the portion 5 between the straps 13 and 14 there is a loop 27.

When the device is in use, the central portion of the portion 5 rests against the palm of the hand, with the plate 23 and hook 24 directed outwardly. The straps 13, 14, and 17 are passed around the back of the hand and are engaged in the buckles 20, 19, and 21, respectively, the strap 18 being passed first through the loop 27 and having its end engaged in the buckle 22. In this position the hook of the plate 25 rests against the fingers of the user, and the plate 25 may be moved by moving the fingers to bring that plate into engagement with the point of the hook 24 to positively grasp husks to be removed, at the same time engaging the husks with the hook of the plate 25. As will be readily seen, the flexi-

bility of the portion 5 permits of the movement of the plate 25 as described.

What is claimed is—

A device of the class described comprising
5 a flexible body portion adapted for attachment
to the hand, a hook carried by the body portion
and arranged to project in the direction
of the fingers of the hand to which the body
portion is attached, and a plate carried by the
10 body portion and arranged for engagement

by the fingers of the user to move it into engagement with the point of the hook, and a second hook carried by the plate.

In testimony whereof I affix my signature in presence of two witnesses.

ANTON J. ROKUSEK.
